UNITED STATES PATENT OFFICE.

HEINRICH STOLLWERCK, OF COLOGNE-ON-THE-RHINE, PRUSSIA, GERMANY,
ASSIGNOR TO GEBR. STOLLWERCK, OF SAME PLACE.

APPARATUS FOR HULLING, ASSORTING, AND CLEANSING COCOA-BEANS.

SPECIFICATION forming part of Letters Patent No. 320,890, dated June 23, 1885.

Application filed February 17, 1885. (No model.)

To all whom it may concern:

Be it known that I, HEINRICH STOLLWERCK, of the city of Cologne-on-the-Rhine, in the Kingdom of Prussia, and German Empire, have invented a certain new and useful Improvement in Apparatus for Hulling, Assorting, and Cleansing Cocoa-Beans, of which the following is a specification, reference being had to the accompanying drawings, and to the letters of reference marked thereon.

This invention relates to a machine or apparatus for hulling, cleansing, and assorting cocoa-beans or similar products; and its object is to reduce, by means of an improved arrangement and combination of feeding, grinding, sifting, blowing, and conveying devices, the cost arising from attending to such machines when in operation, and to prevent, practically, all loss of the sound and valuable parts of the cocoa when the hulls are being separated therefrom.

In the accompanying drawings, Figure 1 is a front view, partly in section, of a machine constructed according to this invention. Figs. 2 and 3 are transverse vertical sections of the same; and Fig. 4 is a transverse horizontal section of the same, showing the arrangement of the ventilators or blowers and their position with regard to the double sieves.

Similar letters of reference indicate corresponding parts throughout the drawings.

$A' A^2 A^3 A^4 A^5$ indicate a system of blowers fixed upon a common shaft, 2, suitably journaled in the frame of the machine, so that all the blowers will rotate with the same speed. The flies or fans of the several blowers vary in size in order that a different amount of air may be blown out from each of the said blowers to suit different sizes of broken cocoa pieces contained in and sifted through rotary assorting-sieves above.

b indicates a conveyer emptying into a crushing-mill, D, connected with an elevator, E, through another conveyer, e. The said elevator empties into a rocking screen, C, having three sieves, $C' C^2 C^3$, connected, respectively, with three pipes, $c' c^2 c^3$.

a is a division-plate, arranged somewhat above the upper sieve, C' , the ends of the said plate being partly cut away, as shown in dotted lines in Fig. 1. c^4 indicates pipes or conduits

connecting the upper part of the said screen C with the rotary assorting-sieves, composed of a number of perforated sections or pipes, $B' B^2 B^3 B^4 B^5$, of sheet metal or other suitable material, fixed in an inclined position upon a common shaft. Two of such rotary sieves are employed in the machine shown in the drawings, the one being mounted upon the shaft 4 and the other upon the shaft 4*. The perforations in the section B^5 are narrower than those in the adjacent section, B^4 , those in B^3 wider than those in B^4 , and so on, so that the last section, B' , will be provided with the widest perforations in each of the said two sieves. The latter are so arranged above the blowers or ventilators $A' A^2 A^3 A^4 A^5$ that the section B^5 , having the narrowest openings, will be above the blower A^5 having the smallest and relatively least powerful flies or fans, and so on, so that the section B' , having the widest openings, will be above the blower A' , having the largest and most powerful fans.

$d d$ indicate conduits connecting the said rotary sieves with the hopper of a pipe, F', emptying into a conveyer, F, connected with a crushing-mill, D', said mill discharging into the said conveyer e likewise.

$H' H^2 H^3 H^4 H^5$ indicate hoppers, arranged, respectively, between the said blowers and sections of the rotary assorting-sieves; and h indicates slides-by means of which the lower discharge-openings of the said hoppers may be closed.

$G' G^2 G^3 G^4 G^5$ indicate double rocking sieves, arranged below the discharge-openings of the hoppers $H' H^2 H^3 H^4 H^5$ and in front of the upper ends of the discharge-openings of the blowers $A' A^2 A^3 A^4 A^5$, respectively.

$K' K^2 K^3 K^4 K^5$ indicate trough-shaped receptacles underneath the said double sieves, each of said receptacles allowing of inserting a transverse sliding plate, k^5 , for a purpose hereinafter specified.

L indicates trough-shaped receptacles connected by means of pipes or conduits g with a conveyer, M, discharging into the elevator E.

N indicates a conveyer arranged underneath the receptacles K' to K^5 , which allows of being rotated in either direction by means of the bevel-gears n', n^2 , and n^3 , as and for a purpose hereinafter described, the said conveyer, according

to the direction of its rotation, discharging either into an elevator, O, or into the said elevator E.

5 I indicates a crank-shaft connected with the said rocking screen C by means of a link, f', and with the said double rocking sieves G' to G⁵ by means of a link, f.

S S indicate slides, provided with the notched handles s, for controlling the amount 10 of air drawn in from the outside by the said blowers A' to A⁵.

7 l indicates a sliding plate, which allows of being adjusted by means of a set-screw, for closing up more or less area of the open rear 15 part of the frame of the machine.

Motion is imparted to the several working parts of the machine, as follows, that is to say: The shaft 2, carrying the said blowers, is provided with the conical or step-shaped pulley 1, driven by any suitable motor, and the shaft 4, carrying one of the said assorting-sieves, is provided with the pulley 3 driven by the same or from any other convenient source of power. The shaft 4, by means of 25 sprocket-wheels 5 and 6 and endless chains, imparts motion to the shaft 4*, carrying the other assorting-sieve and the sprocket-wheel 7, the latter, by means of one of the said endless chains rotating the sprocket-wheel 8, fixed 30 upon the conveyer F, the sprocket-wheel 9 on the conveyer N, and the sprocket-wheel 10 on the conveyer M, whence the said chain runs over the intermediate wheel, 11, and back to the wheels 5 and 7.

35 On the other side of the machine the sprocket-wheel 6, by means of the other of the endless chains, transfers rotatory motion to the sprocket-wheel 12 upon the shaft 13, carrying the said elevator E and the sprocket-wheel 40 14, the latter transmitting its rotatory motion to the sprocket-wheel 15, fitted upon a shaft suitably journaled in the frame of the machine and carrying the pulley 16, said pulley, by means of a twisted belt, rotating the pulley 17 45 on the crank-shaft I. The said shaft I, by means of a twisted belt, imparts rotatory motion to the pulley 18 on the shaft of the crushing-mill D, said shaft carrying another pulley, 19, which, by means of a twisted belt, drives the 50 pulley 20 on the shaft of the crushing-mill D'.

A sprocket-wheel fixed upon the end of the crank-shaft I imparts rotatory motion to the sprocket-wheels 21 and 22, arranged on the shafts of the conveyers b and e.

55 The operation of the improved machine for hulling, cleansing, and assorting cocoa-beans or similar materials is as follows, that is to say: The cocoa-beans, in the proper roasted state, are fed into the conveyer b and thus 60 delivered to the crushing-mill D, whence the crushed product by means of the conveyer e, is fed to the elevator E, which discharges the same upon the rocking screen C, where the said product is sifted into four sizes—that 65 is to say, the finest parts or the dust will pass through all the sieves C' C² C³ and settle on

the bottom C⁴, whence, by the rocking motion of the said screen, it will enter the pipe c', while the next finest parts will be retained by the sieve C³, and the still less fine parts 70 by the sieve C², and enter the pipes or conduits c² and c', respectively. The said pipes c³, c², and c' may discharge into different sacks or other receptacles to collect each size of the siftings separate from the others. The product upon the topmost sieve, C', is shaken 75 around the division or intermediate plate, a, which serves to slacken the movement of the product upon the said sieve C', and to allow the coarse parts of the said product which can 80 not pass through the meshes of the sieve to rise to the surface and to pass through or under the cut-away ends of the said plate, while all the fine parts will go to the bottom, and be brought in contact with the sifting-surface. 85 By this means all the dust and fine particles contained in the broken product are separated therefrom and educted from the machine before the broken product enters the rotary sieves. The said coarse parts, after being 90 shaken around the plate a, are delivered into the sections B⁵ of the said rotary assorting-sieves by means of the conduits c⁴, said sections B⁵ having the narrowest perforations of all the said sections composing the said assorting-sieves, and being arranged above the blower A⁵, having the least powerful fans, as hereinbefore set forth. The finest parts of the coarse product entering the rotary sieves will be sifted through the latter, and the remaining 100 part of the said product will pass on into the sections B⁴, arranged above the somewhat less powerful blower A⁴, said sections being provided with openings somewhat wider than those in the preceding sections B⁵, and allowing the now finest parts of the coarse product to drop out, and so on until the product has passed through the entire length of the rotary sieves, and been assorted in five different sizes, corresponding to the width of the openings in 105 the said five sections. The coarsest parts, which were prevented by their coarseness even from dropping through the wide perforations in the last sections, B', are discharged by means of the conduits d and the pipe F' into the conveyer F, which may deliver the same either 110 into the crushing-mill D, or, as illustrated in the drawings, into the auxiliary crushing-mill D', where the said parts are crushed for a second time, and then, by being delivered into 115 the elevator E by means of the conveyer e, will make the same circuit as before described, to undergo another separating process. The siftings of the five distinct sections B' to B⁵ drop into the hoppers H' to H⁵ respectively, and hence are delivered upon the double rocking sieves G' to G⁵, respectively. The said sieves are preferably composed of double sifting-surfaces having meshes corresponding in width 120 to the perforations in the sifting-surfaces of the said sections B' to B⁵, respectively, with a view to slacken the speed of the siftings in be- 125

ing shaken through the said surfaces, in order that, by thus retarding this part of the sifting process the said siftings may be properly exposed to the action of the blowers. Under 5 this action the lighter parts of the hulls will be blown away from the double sieves, while the heavier and sound parts of the cocoa-beans proper will pass through the sifting-meshes and drop into the receptacles K' to K⁵, respectively, which will thus receive pure cocoa parts 10 free of hulls only.

The power of the air-currents produced by the said blowers is regulated so as to cause the light and pure parts of the hulls to be blown 15 out of the rear part of the machine, while the heavier parts of said hulls with particles of cocoa still adhering thereto, as well as equi-ponderant particles of cocoa proper, what I may term the "intermediate product," are 20 blown into and collected in the funnel-shaped receptacles L, whence, through the conduits g, they are delivered as intermediate product into the conveyer M, and by means of the latter into the elevator E, to be passed again 25 through the machine and undergo another cleansing process.

From the receptacles K' to K⁵ the cleansed and assorted product drops into the conveyer N, which will convey the same either in the 30 one direction into the elevator O to deliver it into some suitable storage-room, (not shown in the drawings,) or in the other direction into the elevator E, again to submit it to a renewed cleansing process, the desired rotary direction 35 of the said conveyer N being obtained by allowing the bevel gear n' to rotate the bevel-gear n² upon the shaft of the conveyer N either in a direct manner by means of a clutch, or by means of the intermediate pinion, n³, as 40 will be readily understood.

In case of the cleansed product being delivered into the elevator E again, some suitable slide or partition, as shown at k⁵ in Fig. 2, should be inserted in the several receptacles K' to K⁵, in order to retain the recleansed product until the conveyer N has emptied the said receptacles from the product resulting from the first circuit. The rotary direction of the conveyer N being then reversed, as 45 above mentioned, and the slides or partitions taken out of the said receptacles, one after the other it will be seen that the different sizes of the broken, hulled, and cleansed product will be separately discharged from the machine, and thus may readily be obtained and collected 50 in an assorted state, while, on withdrawing the said slides from the said receptacles simultaneously, as may be done in some cases, likewise, the different sizes separated from each other by the recleansing process will be mixed 55 again, and delivered in a mixed state into the storage-room by means of the elevator O.

It will be seen that by providing for driving the shaft 2 of the blowers by means of the 60 conical or step-shaped pulley 1, any desired velocity may be readily obtained by simply shifting the driving-belt to suit the different

kinds of products and the relation between the weight of the hulls and that of the kernels; but in order to furthermore obtain exactly the proper amount of blast-air for each blower and each size of the broken product, the air-inlet opening of each blower allows of being opened more or less by means of the slides S, so that the sectional area of the sucking-ports may be varied by the operator at will for each distinct blower. Since the intermediate product blown into the receptacles L allows of being readily inspected by the operator, the latter will always be able to at once 70 control and regulate the power of blast-air required from each of the several blowers. 75

To prevent any particles of the kernels from being blown out of the open rear part of the machine with the hulls, the sliding plate l 80 may be adjusted more or less high by means of its set-screw, and thus regulate the amount of the intermediate product collected.

I wish it to be distinctly understood that I do not confine myself to employing five blowers and a corresponding number of other working parts mentioned, as it will be seen that any suitable number of such blowers and other parts may be used for obtaining a similar result to that described. 90

Having thus described my invention, what I claim as new, and desire to secure by Letters Patent in a machine for hulling, cleansing, and assorting cocoa-beans and similar materials, is— 95

1. The combination of a series of blowers increasing in power from one end to the other of the series, a series of rocking sieves arranged in front of the discharge-openings of said blowers and increasing in the size of their mesh from one end to the other of the series, a series of receptacles located to the rear of said sieves to receive products blown therefrom, and a valve, e, controlling an opening at the rear of said receptacles, substantially as 100 described. 105

2. The combination of a rotary assorting-sieve composed of a series of sections having perforations gradually increasing in size from one end of the series to the other, a series of blowers increasing in power from end to end of the series, a series of rocking sieves arranged between said blowers and rotary assorting-sieve in front of the discharge-openings of said blowers, a series of receptacles located to the 110 rear of said sieves to receive products blown therefrom, and a valve, e, controlling an opening at the rear of said receptacles, substantially as 115 described. 120

3. The combination of a rotary assorting-sieve composed of a series of sections having perforations gradually increasing in size from end to end of the series, a rocking screen composed of a series of finely-perforated sieves arranged one above the other, and a conduit 125 leading from the topmost sieve of the rocking screen into the rotary sieve, substantially as 130 described.

4. The combination of a rotary assorting-

sieve composed of a series of sections having perforations increasing in size from end to end of the series, a rocking screen composed of a series of finely-perforated sieves arranged one above the other, a divider suspended above the top sieve of the rocking screen, and having its lower portion cut away adjacent to its ends, and a conduit leading from said top sieve into the rotary sieve, substantially as described.

5. An apparatus for hulling, assorting, and cleaning cocoa, comprising a grinding-mill, a rocking sieve, a conveyer connecting said mill and sieve, a rotary sieve composed of a series 15 of sections having perforations increasing in size from end to end, a conduit connecting the rocking screen therewith, a series of hoppers located beneath the sections of the rotary

screen, a series of blowers beneath said hoppers of increasing power from end to end of the series, and having adjusting-slides S, a series of rocking sieves in front of the openings to the blowers, a series of receptacles to the rear of said last sieve, having valve-controlled openings, trough-receptacles underneath said 25 sieves and blowers, inclined slides in said trough-receptacles, and a conveyer for said receptacles, substantially as described.

In testimony whereof I have signed my name to this specification in the presence of two 30 subscribing witnesses.

HEINRICH STOLLWERCK.
